UNITED STATES PATENT OFFICE.

JOSEPH RITTIG, OF CAMDEN, NEW JERSEY.

GALVANIC BELT.

SPECIFICATION forming part of Letters Patent No. 276,078, dated April 17, 1883.

Application filed November 17, 1882. (No model.)

To all whom it may concern:

Be it known that I, JOSEPH RITTIG, a citizen of the United States, and a resident of Camden, New Jersey, have invented certain 5 Improvements in Galvanic Belts, of which the following is a specification.

My invention relates to that class of galvanic or electric belts, pads, or bandages in which the negative and positive elements of 10 the battery are so secured or applied to the belt or bandage as to come directly into contact with the body of the wearer; and the main object of my invention is to improve and simplify the construction of these belts or bandages, as more fully described hereinafter.

In the accompanying drawings, Figure 1 is a view of the inner face of a portion of the belt with its galvanic elements; Fig. 2, a reverse view with the outer cover removed; 20 Fig. 3, a perspective view of parts detached; Fig. 4, a section on the line 1 2, Fig. 1; and Fig. 5, a view on a smaller scale of a belt embodying my improvements.

The belt or bandage A may be constructed 25 of leather, fabric, or any other suitable flexible material, and to the inner fold of the belt are secured the zinc and copper or other positive and negative elements, C Z, of the battery, in the manner shown in Fig. 3. The element 30 is preferably in the form of a circular disk, with a central depression and a slot, b, therein. In the inner fold of the belt is formed an opening, a', at the point where the zinc or copper plate is to be applied. Through the slot 35 in the disk and through the opening a' is then passed the split shank of the retainer B, which may be simply the well-known form of paper-fastener, whose head fits into the recess or depression in the center of the disk. The two 40 legs of the retainer are then partially bent back, and the uncovered conducting-wires E, Fig. 2, are wound around them to make a good electrical connection, and then the said legs are bent outward at right angles, as shown in 45 Figs. 2 and 4, and the succeeding disks are applied in the same way. The outer portion, a, of the belt may then be secured in place to inclose the conducting-wires and the bent-up

shanks of the retainers B. The advantages of this construction are that while the disks 50 are effectually held in place as long as may be desired, they can, when worn out, be readily removed and replaced by withdrawing the detachable retainer B.

In front of each disk I secure a piece, D, of 55 flannel or other porous material, as a retainer of moisture to assist in forming the circuit when the belt or bandage is applied to the body of the wearer.

In using galvanic bandages it is, in many 60 cases, desirable to so apply the bandage that the current may be sometimes passed through the body in one direction and sometimes in the opposite direction. This may be usually accomplished by reversing the bandage; but 65 where the latter is not reversible I accomplish the desired object by constructing the bandage as shown in Fig. 5. In this instance the bandage is made in two main parts, A and A', connected together by elastic cords F, and 70 provided with suitable straps and buckles or other fasteners. Each part has its series of zinc and copper plates Z C connected up in quantity or series to two terminal rings, N and P, (N' and P') negative and positive, respectively. In the drawings the terminals P and 75 N' are shown connected by a flexible covered conductor, E', so that when the bandage is applied to the body the current will pass through the wearer's body from the elements 80 of the part A' to those carried by the part A—say from back to front of the body; but by connecting the terminals N and P' by the flexible conductor E' the electric current will flow in the opposite direction, from front to back of 85 the wearer's body.

I claim as my invention—

1. The combination of a bandage or belt and a series of negative and positive disks, Z C, on the surface of the bandage or belt, and 90 adapted to come into direct contact with the wearer's body, with detachable retainers B and conducting-wires passing round the shanks of said retainers, all substantially as set forth.

2. The combination of the bandage or belt 95 and disks Z C, having central depressions and

slots *b*, with retainers *B*, having split shanks passing through the disks, and heads adapted to said depressions.

3. The combination of the two parts of a galvanic bandage, each having positive and negative elements and positive and negative terminals *N P N' P'*, with a detachable conductor, *E'*, substantially as and for the purpose set forth.

In testimony whereof I have signed my name to this specification in the presence of two subscribing witnesses.

JOSEPH RITTIG.
